**FAUCET FOR A BEVERAGE DISPENSER
OR THE LIKE**

Walter A. Plagenberg, St. Louis County, Mo., assignor to
White Cross Manufacturing Co., Inc., a corporation of
Missouri

Filed May 28, 1965, Ser. No. 85,497

Term of patent 14 years

(Cl. D2—3)

FIG. 2

FIG. 1

FIG. 3

FIG. 4

FIG. 5

FIGURE 1 is a side elevational view of a faucet for a beverage dispenser or the like, showing my new design. FIGURE 2 is a top plan view thereof.

FIGURE 3 is a rearward end view thereof.

FIGURE 4 is a bottom plan view thereof.

FIGURE 5 is a front end view thereof.

The dominant features of my design reside in the portions shown in full lines.

I claim:

The ornamental design for a faucet for a beverage dispenser or the like, and described as shown.
